UNITED STATES PATENT OFFICE.

ANDREW F. DIERDORFF, OF LOS ANGELES, CALIFORNIA.

STABILIZING LIFTING-PLANE FOR FLYING-MACHINES.

1,026,079.

Specification of Letters Patent.

Patented May 14, 1912.

Application filed September 5, 1911. Serial No. 647,776.

To all whom it may concern:

Be it known that I, ANDREW F. DIERDORFF, a citizen of the United States, residing in the city and county of Los Angeles, State of California, have invented a new and useful Stabilizing Lifting-Plane for Flying-Machines, of which the following is a specification.

An object of this invention is to provide a lifting plane so constructed as to automatically stabilize flying machines against excessive or dangerous inclination of the machine in any direction. This desirable result is accomplished by providing the flying machine with a partly inflated lifting plane constructed somewhat like the body portion of a pair of bellows and extending across the machine so that excessive pressure against the under side of one portion of said bellows-like plane will change the angle of the under surface of said portion to diminish the lifting power thereof, the air in said portion being forced to a portion of the bellows-like plane on the other side of the machine so as to form a lifting plane of greater angle at the latter side of the machine, thus effecting lateral balancing of the machine.

Stabilizing with a view to preventing excessive inclination to the front or rear is obtained by reason of the bellows-shaped lifting plane automatically conforming its lower side to the varying air pressure in such a manner as to right the machine from any dangerous dips upon which it may start to enter.

Referring to the accompanying drawings which illustrate the preferred embodiment of the invention, Figure 1 is a perspective view of the front portion of an aeroplane showing the same provided with two lifting planes constructed according to the principles of this invention; Fig. 2 is a cross section of the upper lifting plane on line x^2 of Fig. 1; Fig. 3 is an enlarged broken cross section on line x^3 of Fig. 2.

Referring in detail to the drawings, my newly invented lifting planes 1 and 2 are shown in Fig. 1 mounted respectively in the upper and the lower portions of the frame 3 of an aeroplane of the biplane type. It is to be understood, however, that the invention is not limited to use upon biplanes but may be applied to other types of flying

machines including lifting planes of any character.

The upper plane 1 and lower plane 2 are similarly constructed and therefore only one need be described in detail. The upper lifting plane consists of a plurality of bellows-shaped sections 4 and 5 and the lower lifting plane likewise consists of the bellows sections 6 and 7. The bellows-shaped sections 4 and 5 are similarly constructed, the pointed portion of the bellows being forward. Each bellows section is desirably maintained in about a half inflated condition. Said bellows sections are connected with each other by a runway 8 large enough to permit excessive air pressure upon the underside of one bellows to be quickly communicated to the bellows at the other side. This feature is what is relied upon to stabilize the machine against one wing or the other dipping too much toward the earth. These bellows-shaped lifting planes will be formed of any suitable air-tight fabric and will be somewhat flexible upon the under side so that the air pressure will tend to make the center portion (from front to rear) of the lower surface of the bellows curve upwardly and thus assume the character of curve which has been scientifically proved to afford the best lifting power.

An inflating tube 9 provided with a valve 11 affords means to inflate the lifting planes or to deflate the same if desired, said tube communicating with a tube 12 which connects the runway 8 of the upper plane with the runway 8 of the lower plane. Said tube 12 will equalize the air pressure between the bellows sections of the upper plane and those of the lower plane because said runways 8 are in communication with the bellows sections of said planes.

14 is the usual propeller.

The contracted neck 8 of each plane permits the bellows sections on each side to operate independently to equalize automatically the lifting power of the atmosphere on opposite sides of the mid-width of the machine. This result is attained by reason of the bellows sections of said plane containing air which may flow freely from one side to the other through said neck or runway 8.

In operation, if an air current strike with unusual force against the under side of the bellows at one side of the machine, a de-

flating movement of said bellows will take place, lessening the angle of incidence of the lower surface thereof and therefore lessening the lifting power of the atmosphere at that side. At the same time, more air will be forced through the neck 8 into the bellows at the other side of the machine increasing the angle of incidence of the bellows last named and tending to restore the balance.

10 The contracted neck or runway 8 connects the two members of each of the lifting planes, said neck affording free communication between the bodies of air confined within the bellows.

15 I am aware that, in flying machines, various gas-bags have heretofore been provided of a more or less wedge shape form, but am not aware that an air-filled container 20 has as yet been devised so constructed that it could properly be called a "bellows" and adapted to perform the function of a lifting plane.

1 claim:

25 1. In a flying-machine, a bellows-shaped lifting plane on each side of the machine, each of said planes containing air, and means affording atmospheric communication between the chambers of said planes to 30 permit the pressure of the outer air against the under side of one of the planes to au-

tomatically force air into the chamber of the other plane to change the angle of incidence of the under side thereof.

2. A flying machine provided with a 35 transverse lifting plane, said plane consisting of the bottom walls of two communicating bellows, and a contracted neck connecting said bellows, the deflation of one of said bellows causing the inflation of the 40 other.

3. A flying machine provided with two superposed transverse lifting planes, said planes each consisting of the bottom walls of a set of two communicating bellows, a 45 horizontal way or conduit affording communication between the bellows of each set, and another conduit to afford atmospheric conduits and thereby place all of said bellows 50 in atmospheric communication with each other.

In testimony whereof I have hereunto signed my name in the presence of two subscribing witnesses at Los Angeles, in the 55 county of Los Angeles and State of California; this 31st day of August 1911.

ANDREW F. DIERDORFF.
